ROLLING MILL

Stephen Badlam, Rosslyn Farms Borough, Pa.

Application November 25, 1931, Serial No. 577,277

4 Claims. (Cl. 80—41)

The invention relates to rolling mills, and particularly mills for rolling plates, skelp, sheets, strip, and other sheet-like products.

In the rolling mill art in both hot and cold rolling, it is well known that one of the factors influencing the shape of a delivered piece is the uneven distribution of heat along the length of the roll body. This has the effect of making the shape of the active pass, that is to say, the shape 10 of the pass while the piece is engaged by the rolls, different from the shape of the pass when the rolls are cold and no piece is engaged by them, as well as different at successive stages of the rolling operation.

This change of shape due to heat is comparatively small in the case of sections such as squares, rounds, shapes, etc., in which the width is not great in proportion to the thickness, but is of material importance in the case of plates, 20 and becomes a dominant factor in the case of sections such as sheets, strips, skelp, and the like, in which the width is great in proportion to the thickness.

The change in shape of rolls due to heat may arise from two among other causes; first, from heating of the necks, due to bearing friction which causes the ends of the roll body to expand more than the center of the roll body. Second, 30 the heating of the center of the roll body due to the heat derived from hot metal passing through the rolls, or evolved due to the mechanical work done upon the metal. The first causes a thinning of the edges of the sheet due to the expansion of the ends of the rolls, and the second causes a thinning of the center of the sheet due to the expansion of the center of the rolls.

Several expedients have been used in the past to overcome the effect of this uneven heating, such as turning the rolls to a non-cylindrical 40 shape in the cold so that, after the rolls have been in use for a period of time and become heated, the shape of the active pass will become truly cylindrical. This may take the form of making the cold rolls either hollow or else 45 crowned in the centers, according to whether the effect of the heating is to puff up the centers or to expand the ends of the rolls. Another expedient is to use only a minor part of the body of a roll as a working face, whereby the conduction of heat from the bearings is decreased and made substantially uniform throughout the portion used as a working face. Still other expedients are the application of a cooling medium, such as water, on portions of the body of a roll, 50 or on its bearings, to decrease the heat thereof,

and the application of gas or oil flames on portions of a roll body to increase its heat and consequent expansion.

The object of the present invention is to provide improved means for dissipating the heat of rolls and substantially preventing its flow from the necks to the body and vice-versa.

The invention is somewhat diagrammatically illustrated in the accompanying drawing, of which Fig. 1 is a face view of a pair of working rolls for a mill for rolling sheet-like metal; and Fig. 2 a face view of a set of working and packing rolls for a backed-up mill for the same purpose.

In the practice of this invention its stated object is accomplished by providing each end of a roll body, between its working face and neck portions, with exposed attenuated heat-dissipating surfaces. These surfaces preferably take the form of radially-disposed annular or helical fins or vanes, the exposed surfaces of which are materially greater than the working face of the roll for a corresponding portion of its length. When heat-dissipating fins are used, they may be formed integrally with the roll, or they may be in the form of disks of copper or other good heat-conducting metal suitably attached to the roll between its working portion and necks. The cooling of these heat-dissipating surfaces may be either by means of the air surrounding them or by the use of a cooling medium such as air, water or oil applied 30 to them.

In Fig. 1 of the drawing there is shown a pair of working rolls having working portions 1 and necks 2, between which there are a plurality of annular fins 3 forming attenuated heat-dissipating surfaces. If desired, these surfaces may be continuously cooled by means of a cooling medium, such as water or oil, flowing on them from a header 4 connected to a pipe 5 leading from a suitable source of supply. The fins 3 being arranged in a zone or section of the rolls between their working portions and necks, afford surfaces for dissipating heat flowing either from the bodies into the necks or from the necks into the bodies of the rolls, depending upon well known variable conditions of 45 rolling.

In Fig. 2 there is shown a backing-roll mill comprising working rolls 10 and backing rolls 11. In mills of this type pressure is applied to the rolls through the necks 12 of the backing rolls, and accordingly frictional heat is generated in the necks of the backing rather than in those of the working rolls. In this case the backing rolls are provided with fins 13 between their necks and central working portions, such fins forming attenu- 50 55

ated heat-dissipating surfaces particularly for dissipating heat generated in the necks of the rolls. In this embodiment of the invention fins 13 are shown as being enclosed in fluid-tight casings 14 into which cooling fluid is introduced through pipes 15 and withdrawn through pipes 16. The fins are thus kept in continuous contact with the cooling medium circulating within the casing. By providing helical fins such as illustrated, the cooling medium may be caused to circulate in the casings in a direction counter to that of the flow of heat from one to another portion of a roll, although annular fins such as shown in Fig. 1 may be similarly used in casings 14.

15 Working rolls 10 are shown in Fig. 2 as being provided with a modified form of fins 17, these being disks of copper or other good heat-conducting metal suitably attached to the rolls between their working surfaces and necks. Manifestly 20 this form of fins may be used on the rolls of Fig. 1 or on the backing rolls 11 of Fig. 2. In fact any of the three forms of fins herein disclosed may be used on any of the rolls.

According to the provisions of the patent statutes, I have explained the principle and operation 25 of my invention, and have illustrated and described what I now consider to represent its best embodiment. However, I desire to have it understood that, within the scope of the appended 30 claims, the invention may be practiced otherwise than as illustrated and described.

I claim:

1. In a rolling mill, a roll having a central work-

ing portion, bearings at its ends, and provided between its working portion and bearings with attenuated heat-dissipating surfaces, casings enclosing said heat-dissipating surfaces, and means for circulating a cooling medium through said casings and in contact with said surfaces. 5

2. In a rolling mill, a roll having a central working portion, bearings at its ends, and provided between its working portion and bearings with attenuated heat-dissipating helical fins, casings 10 enclosing said fins, and means for circulating a cooling medium through said casings and in contact with said fins.

3. In a rolling mill for rolling thin wide flat metal, a pair of rolls each having a central working portion, bearings at its ends, and provided between its working portion and bearings with exposed attenuated surfaces for dissipating heat flowing to and from the working portion and bearings of the roll, whereby to inhibit the effect of 20 heat on the active pass formed by the working portion of the rolls.

4. In a rolling mill for rolling thin wide flat material, working rolls and backing rolls, said backing rolls each having a body portion engaging the adjacent working roll and bearings at each end, and provided between said body portion and said bearings with exposed attenuated surfaces for dissipating heat flowing to and from the body portion and the bearings, whereby to inhibit the 30 effect of said heat on the active pass formed by the working rolls.

STEPHEN BADLAM.
